US00D791804S

(12) **United States Design Patent** (10) **Patent No.:** **US D791,804 S**
(45) **Date of Patent:** **** Jul. 11, 2017**

(54) **DISPLAY SCREEN WITH GRAPHICAL USER INTERFACE**

(71) Applicant: **Microsoft Corporation**, Redmond, WA (US)

(72) Inventors: **Emmanuel Reyes**, Lynnwood, WA (US); **Benjamin Perry**, Redmond, WA (US); **John Snavely**, Seattle, WA (US); **Xiaoji Chen**, Seattle, WA (US); **Ryan Phillips**, Seattle, WA (US); **Jeff Fleischmann**, Seattle, WA (US); **Mitchell Johnson**, Seattle, WA (US); **Nicholas Robinson**, Sammamish, WA (US); **Joseph Wheeler**, Sammamish, WA (US); **Nathan Johnson**, Kirkland, WA (US); **Brian Ralphs**, Redmond, WA (US); **David Gardner**, Covington, WA (US)

(73) Assignee: **Microsoft Corporation**, Redmond, WA (US)

(**) Term: **15 Years**

(21) Appl. No.: **29/535,284**

(22) Filed: **Aug. 5, 2015**

(51) LOC (10) Cl. **14-04**

CLAIM

The ornamental design for a display screen with graphical user interface, as shown and described.

DESCRIPTION

The FIGURE is a front view of a display screen with graphical user interface showing our new design.

The outermost broken lines illustrate a display screen and form no part of the claimed design. The remaining broken

(Continued)

lines, illustrating portions of the graphical user interface,
form no part of the claimed design.

1 Claim, 1 Drawing Sheet
